UNITED STATES PATENT OFFICE.

WILLIAM L. BECK AND LAWRENCE W. TILFORD, OF KEVIL, KENTUCKY.

POULTRY-COOP.

1,189,040.

Specification of Letters Patent. Patented June 27, 1916.

Application filed January 19, 1915. Serial No. 3,158.

To all whom it may concern:

Be it known that we, WILLIAM L. BECK and LAWRENCE W. TILFORD, citizens of the United States, residing at Kevil, in the 5 county of Ballard, State of Kentucky, have invented certain new and useful Improvements in Poultry-Coops; and I do hereby declare the following to be a full, clear, and exact description of the invention, such as 10 will enable others skilled in the art to which it appertains to make and use the same.

This invention relates to certain novel and useful improvements in poultry coops or crates of the type usually employed for 15 confining and shipping chickens.

In carrying out our invention it is our purpose to provide a coop which is so constructed as to permit of adequate ventilation, and at the same time such coop will 20 possess manifest advantages from a sanitary standpoint, in that it may be readily and thoroughly cleaned when desired.

Another object of our invention is the provision of a coop of this character which 25 is equipped with a sliding door through the medium of which the chickens may be placed in and removed from the coop, said door having means for normally drawing and holding the same in closed position so 30 that said door must be held open for the purpose of having access to the inside of the coop, for the instant the holding action of the operator on the door is removed, the door will be drawn to its closed position, 35 thereby preventing the escape of poultry from the coop, such as would occur if the door were accidentally left open.

It is also our purpose to provide a coop 40 of this character which will embody the desired features of simplicity, durability, efficiency and strength, which is so constructed that it may be shipped long distances and used for a comparatively long time without being broken or otherwise damaged, and 45 which embodying as it does but relatively few parts, may be manufactured and marketed at a relatively low cost.

With the above recited objects and others 50 of a similar nature in view, our invention consists in the construction, combination and arrangement of parts set forth in and falling within the scope of the appended claims.

In the accompanying drawings: Figure 1 55 is a top plan view of a coop embodying our

invention. Fig. 2 is a central, vertical longitudinal sectional view through the same. Fig. 3 is a plan view of a portion of the top of the coop looking at the underside of the top and showing the door in its closed position, this view illustrating clearly the springs for maintaining the doors so closed. Fig. 4 is a vertical cross sectional view taken on the line 4—4 of Fig. 1. Fig. 5 is a top plan view of a portion of the top of the 60 coop and showing the door in partially closed position. Fig. 6 is a cross sectional view on the line 6—6 of Fig. 1 looking in the direction of the arrow.

Before entering into detailed description 70 of our improved coop, we will briefly state that it comprises a box-like skeleton frame having a solid bottom, while the ends are closed by sections of wire netting. The vertical sides and the top of the coop are 75 also formed of a single piece or section of wire netting, such piece of netting being fastened at one of its longitudinal edges to the longitudinal bottom bar at one side of the box-like frame, the netting being 80 then carried upward over and across the top of the box-like frame and thence downward at the opposite side, the other longitudinal edge of the netting being fastened to the other longitudinal bottom bar of the 85 frame so that both the longitudinal sides and the top of the frame are covered by this wire netting. The netting is preferably formed of transverse and vertical strands of relatively heavy wire, spaced a considerable distance apart, and a portion of the netting covering the top of the coop is provided with a relatively large central opening through which access may be had to the 90 coop. This opening is intended to be closed 95 by a door which slides upon L-shaped angle bars, the door being normally drawn to its closed position by means of suitable springs. The strands of the netting overlie the edges of the door, as clearly shown in Fig. 1 of the 100 drawings, so that the door cannot be accidentally elevated or shoved upward out of the rails or bars on which it travels, as the top netting acts to confine the door on the rails and at the same time such door may 105 slide freely. The corners of the coop are provided with suitable corner shields of metal or other material to act as buffers in the well known manner.

Referring now to the accompanying 110

drawings in detail, the letter A indicates the box-like frame of the coop, this frame being preferably constructed of strips of wood. The solid bottom of the coop is shown at 1, and may be made up of wooden boards or of sheet metal. The ends of the box-like frame are covered by sections of wire netting, shown at 2-2, this netting being preferably made of relatively heavy wire, composed of longitudinal and transverse strands spaced a relatively great distance apart. The longitudinal sides and the top of the frame are covered with a piece of netting B, this netting being fastened at one 10 of its longitudinal edges to one of the longitudinal bottom bars 3 of the frame, being then carried up over the adjacent longitudinal top bar 4, thence across the top and down over the other top longitudinal bar 5 and fastened at its other end to the other longitudinal bottom bar 3, in the manner 20 readily understood, so that the two vertical sides and the top of the crate are made up of a single section of wire netting. The ends 25 of the frame are braced by intermediate vertical posts 6, while the sides are braced by similar intermediate vertical posts 7. The corner posts of the frame are indicated at 8. The top end bars of the frame are 30 shown at 9 and extending longitudinally of the top of the frame are spaced metallic rails 10. These rails are in the form of angle irons, and specifically are in the nature of L-bars, and at their ends the vertical flanges 11 of the bars are cut away to 35 form shoulders 12 which fit against the top bars 9, the end sections of the horizontal flanges 13 of these bars 10 being fastened by rivets 14 to the under faces of the top end 40 bars 9. These two bars 10 are suitably spaced apart and extend in parallelism longitudinally of the top of the coop beneath the netting covering the top and constitute runners for the sliding door D, the door 45 sliding on the horizontal flanges 13 of the rails, and such door is confined against lateral displacement by the vertical flanges 11 of the rails. Bolted to the rails as at 15 and extending transversely between the 50 same is a stop bar 16, the forward edge 17 of this bar projecting slightly inward of the transverse wire 18 which forms one transverse side of the central opening B' of the coop, so that when the door is in its 55 closed position it will abut at one end against this edge 17 of the bar 16, and when in such closed position the transverse end 19 of the door will lie beneath the transverse wire strand 20 which forms the other transverse side of the opening B'. Likewise the 60 longitudinal strands 21 and 22 overlie the longitudinal sides of the door as clearly shown in Fig. 1 so that the door cannot be pushed or elevated from the rails to such an extent as to entirely disconnect it from

the coop and thus permit the escape of the chickens. In order to draw the door normally to its closed position, we provide one or more relatively large powerful coil tension springs 23 pivotally connected to the 70 underside of the door by a hook and eye as at 24, and likewise detachably connected as at 25 by a hook and eye to the underside of one of the top end bars 9 of the frame A. The solid bottom of the coop may be reinforced by a suitable number of metallic strips such as shown at 26, and the corners of the coop are further provided with metallic corner shields 27 of any suitable 75 character.

The numeral 28 indicates an approximately U-shaped reinforcing hanger wire, the ends of which are coiled as at 29 about and around the strand 20 at the top of the coop, the wire passing beneath and in contact with the rails 10. The purpose of this wire is to hold the top section B of the wire netting down in position over the rails so that such top section of netting will always 85 perform its function of constituting a top 90 guiding member for the sliding door.

From the above description, taken in connection with the accompanying drawings, the construction and manner of employing our invention will be readily understood. 95 When it is desired to place the chickens in the coop the door D is grasped and pulled open or to the right in Fig. 1, against the tension of the springs 23 so that such springs will be stretched as shown in Fig. 5. When 100 the chickens have been placed in the coop, or removed as the case may be, the operator releases the door and the springs will restore it to its normal closed position as shown in Figs. 1, 2 and 3 of the drawings. 105

It will be noted that we have provided an exceedingly simple, yet strong and durable coop, which possesses manifest advantages from the standpoint of cleanliness, capability of ventilation and the like. 110

While we have herein shown and described one particular embodiment of our invention, we wish it to be understood that we do not confine ourselves to all the precise details of construction herein set forth by way of illustration, as modifications and variations may be made without departing from the spirit of the invention or exceeding the scope of the appended claims. 115

What we claim is:

1. A poultry coop comprising a skeleton box-like frame having a solid bottom and having the ends thereof covered with sections of wire netting, wire netting forming the longitudinal sides and the top of the coop, the netting of the top having a relatively large opening in the center thereof, parallel rails fastened at their ends to the top portion of the frame, a door sliding on said rails, such door being held from up- 125 on said rails, such door being held from up- 130

ward movement away from the rails by the wire netting constituting the top of the coop, a stop bar extending transversely between the rails and limiting the movement of the door to its closed position, and a spring normally drawing the door to closed position against the stop bar.

2. In a poultry coop, a frame covered with netting, a pair of oppositely disposed L-shaped rails arranged beneath the netting of the top of said coop to extend longitudinally thereof in parallel relation, the said top netting being free from said rails and cut away adjacent the central portion thereof

to provide an opening between said rails, 15 a door arranged to slide upon the horizontal portions of said rails, a stop between said rails for limiting the movement of said door in one direction, and a spring for normally holding said door engaged with said 20 stop.

In testimony whereof, we affix our signatures, in the presence of two witnesses.

WILLIAM L. BECK.

LAWRENCE W. TILFORD.
